UNITED STATES PATENT OFFICE.

HARRY E. WILLIAMS, OF LOUISVILLE, KENTUCKY, ASSIGNOR TO DOW WIRE & IRON WORKS, OF LOUISVILLE, KENTUCKY, A CORPORATION.

CONVEYER.

1,095,255.

Specification of Letters Patent.

Patented May 5, 1914.

Application filed May 28, 1912. Serial No. 700,192.

To all whom it may concern:

Be it known that I, HARRY E. WILLIAMS, a citizen of the United States, residing at Louisville, in the county of Jefferson and State of Kentucky, have invented certain new and useful Improvements in Conveyers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to the class of conveyers but more particularly to a conveyer which can be employed for both raising and lowering articles, packages, boxes, crates and the like, and the invention has for its object to provide a combined raising and lowering conveyer which is so constructed and arranged that articles, packages, boxes, crates and the like can be raised and deposited on any desired floor in the building and in which articles, packages, boxes, crates and the like can be conveyed from any floor in the building in a downward direction.

A further object of the invention is to provide the conveyer with certain fire proof doors arranged at each floor or story in the building in such manner that they will automatically close in the event of fire.

A further object of the invention is to provide a conveyer which is so constructed and arranged as to receive the articles, packages, boxes, crates and the like and convey the same either upwardly or downwardly without injuring or breaking the articles, packages, boxes, crates and the like.

A further object of the invention is to provide a conveyer of the character described which is extremely simple in its construction, cheap and easy to manufacture, strong, durable and efficient.

With these and other objects in view the invention consists in the construction of the conveyer and in its component parts; and the invention consists in the novel arrangement for raising and handling the articles, packages, boxes, crates and the like at the lower end of the conveyer in such manner that the same cannot be injured or broken by the conveyer chain and flights.

The invention further consists in the novel

construction for depositing articles, packages, boxes, crates and the like at any desired floor throughout the length of the conveyer.

The invention further consists in the novel construction and arrangement of the safety fire doors.

The invention further consists in certain other novel details of construction and in combinations of parts, all of which will be first fully described and afterward specifically pointed out in the appended claims.

Referring to the accompanying drawings forming a part of this specification: Figure 1 is a side elevation of a raising and lowering conveyer constructed in accordance with this invention. Fig. 2 is a top plan view of the same. Fig. 3 is a vertical longitudinal sectional view. Fig. 4 is a transverse vertical sectional view taken on line 4-4 of Fig. 1. Fig. 5 is a transverse sectional view taken on line 5-5 of Fig. 1. Fig. 6 is a transverse sectional view of the frame and floor of the conveyer taken on line 6-6 of Fig. 1, and Fig. 7 is a fragmentary longitudinal vertical sectional view showing a modified construction of the arrangement of intermediate doors or openings for delivering an article, package, box, crate and the like at intermediate openings throughout the length of the conveyer.

Like numerals of reference indicate the same parts throughout the several figures in which—

1 indicates the conveyer which comprises the longitudinal lower frame pieces 2 (Fig. 90 6) and the upper longitudinal frame pieces 3, the lower frame pieces 2 being preferably constructed of channel-iron as shown, while the upper frame pieces 3 are constructed of angle-iron. The lower frame pieces 2 are connected together at intervals by means of the transverse connecting floor supporting braces 4, upon which transverse braces 4 are arranged the longitudinal floor pieces 5 in the manner as shown in Fig. 6, 100 said longitudinal floor pieces 5 extending the full length of the conveyer and forming the floor upon which articles, packages, boxes, crates and the like slide on their upward or downward movement on the conveyer. The upper and lower longitudinal frame pieces 2 and 3 are connected together 105 at intervals by vertical frame pieces 6 of

angle-iron or of any other suitable material, and the said longitudinal frame pieces are also connected together by truss pieces 7 arranged conveniently to add strength and 5 rigidity to the structure.

8 indicates the upper sprockets for the conveyer chain and 9 indicates the lower sprockets over which sprockets the conveyer chain 10 travels, said conveyer chain 10 being 10 composed of a series of links 11 connected together by transverse pins 12 upon which are mounted rollers 13, said rollers 13 rolling on the upper and lower longitudinal frame pieces 2 and 3 in the manner as illustrated in Figs. 4 and 5. By means of this 15 construction the friction of the chains is reduced to a minimum.

In order to maintain the chains in their proper relative positions I provide at the 20 lower bend of the conveyer a pair of guide pieces 14 curved in accordance with the bend in the conveyer under which the conveyer chains travel, and at the bend in the upper frame pieces 3 I provide similar guides 15, which guides 15 are vertically adjustable at 25 16, in order to take up the slack in the conveyer chains and to adjust the tension of the same on its sprockets 8 and 9. The conveyer chain is preferably driven at the top 30 end of the conveyer by a pulley 17 (Fig. 4) driving a pair of gear wheels 18 mounted on a transverse shaft 19, said gear wheels 18 meshing with pinions 20 mounted on the sprocket wheel shafts 21 although, as is, 35 of course, apparent, the conveyer chains can be driven from the lower sprockets 9 by the simple application of the gearing just described to the lower end of the conveyer.

Referring now particularly to Fig. 3 it 40 will be seen that the floor of the conveyer terminates at the point 22 under the lower sprockets 9 while a conveying apron 23 mounted on rollers 24 is disposed in line with the floor of the conveyer, said apron 23 being driven by means of a pinion 25 (Fig. 1) mounted on the shaft of the forward apron roller 24, said pinion 25 meshing with the partially toothed gear wheel 26 mounted on the shaft 27 of the lower 50 sprocket wheels 9 for a purpose which will be presently described. Approaching the endless apron 23 is a short conveyer 28 composed of the rollers 29 by which the articles, packages, boxes, crates and the like are 55 conveyed to the apron 23. Referring in this connection to Fig. 2 it will be seen that I interpose between the end of the short conveyer 28 and the outer end of the conveyer apron 23 two stops 30 which stops are arranged 60 to prevent the passage of an article, package, box, crate and the like on to the endless apron 23; while it will be seen from Figs. 2 and 3 that I dispose on the apron 23 a projection 31, which projection 65 is moved with the apron 23 and passed up

between the end of the apron 23 and the inner end of the short conveyer 28 in the manner as illustrated in Figs. 2 and 3.

While the drawings illustrate a single intermediate chute or conveyer between the 70 ends thereof it is of course perfectly apparent that as many intermediate chutes can be arranged as there are floors or stories in the building and it is simply a matter of duplicating the chutes in order to make the 75 conveyer applicable to a building of any height.

Referring now to Figs. 1 and 3 it will be seen that the floor 5 is provided with an opening 32 and communicates with an inclined 80 chute 33 in such manner that an article, package, box, crate and the like being conveyed by the conveyer chains will be deposited on the said chute 33 and is led by gravity onto the lower conveyer 34. As before 85 stated, as many of these chutes are arranged in the conveyer as there are stories in the building, providing of course that the conveyer extends the entire height of the building, and when it is desired to convey articles, packages, boxes, crates and the like either up or down, without having them deposited at intermediate points, a removable floor-section 35, shown in dotted lines in Fig. 3 and in full lines in Fig. 1, is arranged at 90 the openings 32 in order to provide a continuous floor the entire length of the conveyer, and it is obvious that any one of the said removable floor-sections 24 can be removed in order to deposit articles, packages, 100 boxes, crates and the like at any desired point intermediate the ends of the conveyer. Referring in this connection to Fig. 7, however, it will be seen that in place of the removable floor section 5, I can pivot the section 36 at the point 37 and so hold the section 36 by a weight 38 so as to maintain the said section 36 normally in proper position, and I can arrange a slide 39 to pass under the end 40 of the hinged section 36 in order 105 to maintain the section 36 in its normal position during the passage of the articles, packages, boxes, crates and the like either upwardly or downwardly of the conveyer, and when it is desired to deposit an article, package, box, crate and the like at any intermediate point along the length of the conveyer it is simply necessary to move the slide 39 into position shown in full lines 110 in Fig. 7, and as the article, package, box, crate and the like reaches the hinged section 36 the weight of the same will cause said hinged section to swing down into position shown in dotted lines in Fig. 7 and cause the weight 38 to be raised into position shown 115 in dotted lines in said figure which will cause the article, package, box, crate and the like to be lowered onto the end 41 of the roller conveyer 34 and as soon as the article, package, box, crate and the like is thus de- 120 125 130

livered on the roller conveyer 34, the section 36 is raised by gravity into its normal position as shown in Fig. 7.

Referring now to the conveyer chains it will be seen that at intervals thereon there are depending brackets 42 which are connected together by transverse flights 43 having thereon rollers 44 which transverse flights engage the article, package, box, 10 crate and the like in order to convey the same upwardly and downwardly of the conveyer. For the purpose of having the conveyer flights engage the articles, packages, boxes, crates and the like in a proper manner at the bottom of the conveyer so that there will be no possibility of damage or breakage to the articles, packages, boxes, crates and the like conveyed I arrange the construction as illustrated in Figs. 1 and 3 15 which has been previously described and which operates as follows: When an article, package, box, crate and the like to be conveyed is placed on the lower roller conveyer 28 the said article, package, box, crate and the like engages the stops 30 and is held in a stationary position until the extension 31 on the apron 23 comes into position shown in Figs. 2 and 3, and as the conveyer apron 23 carries the projection 31 in an upward 20 direction the said projection comes under the end or forward edge of the article, package, box, crate and the like and raises the same clear of the stops 30 and onto the conveyer apron 23 in such manner that the article, package, box, crate and the like is conveyed by the said apron 23 onto the floor of the conveyer. When the article, package, box, crate and the like is thus conveyed a chain flight is in position to engage the same 25 from behind to raise and elevate the same on the conveyer. However, as the partially toothed or mutilated gear wheel 26 and the pinion 25 are so timed that the conveyer apron 23 is not moved whenever one of the 30 transverse flights is passing around the sprocket wheels. This system of gearing is so timed that the endless conveyer apron 23 makes only one revolution and is then stopped. By means of this construction it is 35 perfectly apparent that the articles, packages, boxes, crates and the like can never come on the conveyer apron 23 at a time when the same would be in position to be struck with the chain flights in such manner as to damage and injure the same for the reason that the conveyer apron 23 is at rest and is at a full stop whenever the chain flights are making the turn around the sprocket wheels 9 so that by this arrangement the articles, packages, boxes, crates and the like are delivered to the conveyer floor at a time when the conveyer flights are in a safe position so as not to contact with and damage the article, package, box, crate and 40 the like. This as is perfectly apparent is a

material feature of this invention for the reason that without this safe-guard delicate and fragile articles, packages, boxes, crates and the like would be liable to severe injury and breakage, while heavy and tough articles, packages, boxes, crates and the like would severely injure the chain flight should they be under the same when the said flight is making its turn around the lower sprocket wheels.

Having thus fully described the invention the operation of the same is apparent from the foregoing description taken in connection with the accompanying drawings. As a matter of safety I provide as many fire doors in the conveyer as there are floors to the building through which the conveyer passes, said fire doors being clearly illustrated in Figs. 1 and 3, and are constructed preferably of sheet iron, the doors 45 being hinged at 46 and suspended in the position shown in Figs. 1 and 2 by means of a fuse 47, which fuse 47 is of such character that the same will part when heated and allow the doors 45 to drop into a horizontal position to completely close the openings in the floors through which the conveyer passes, thus forming effectually a fire door in order to prevent the passage of flame from one floor to the other through the conveyer 95 openings.

Having thus fully described the invention it is of course apparent that the same is capable of certain changes and modifications in the construction which would clearly fall within the limit and scope of this invention, and I consider myself clearly entitled to all such changes and modifications which fall within the terms of the following claims.

What I claim as new and desire to secure by Letters Patent of the United States is:—

1. A conveyer for elevating articles, packages, boxes, crates and the like comprising a suitable frame-work and means for propelling articles, packages, boxes, crates and the like up the conveyer, a conveyer-apron at one end of said conveyer, a second conveyer associated with said conveyer-apron, means intermediate said second conveyer and said conveyer-apron for stopping said articles, &c., means on said conveyer-apron for engaging the stopped articles &c., to lift the latter from said second conveyer onto said conveyer-apron, said propelling means effecting the removal of said articles &c., from said conveyer-apron onto the main elevator.

2. A conveyer for elevating articles, packages, boxes, crates and the like, including a frame-work, an endless belt of flights and means for actuating the same, a conveyer-apron at one end of said conveyer, a second conveyer associated with said conveyer-apron, means intermediate said second conveyer and said conveyer-apron for stopping said articles, &c., means on said conveyer-

apron for engaging the stopped articles, &c., to lift the latter from said second conveyer onto said conveyer-apron, said endless belt of flights effecting the removal of said articles, &c., from said conveyer-apron onto the main conveyer.

3. A conveyer for elevating articles, packages, boxes, crates and the like comprising a propelling means, a conveyer apron at one end of said conveyer, intermediate means between the said propelling means and the said conveyer apron to drive the said conveyer apron intermittently, a second conveyer assembled with said conveyer-apron, means between said second conveyer and said conveyer-apron for stopping said articles &c., means on said conveyer-apron for engaging said stopped articles &c.; said conveyer apron being arranged to deliver articles, packages, boxes, crates and the like to the said conveyer, substantially as described.
4. A conveyer for elevating articles, packages, boxes, crates and the like comprising a propelling means, a conveyer apron at one end of said conveyer, a conveyer associated with said conveyer apron arranged to deliver to said conveyer apron articles, packages, boxes, crates and the like to be propelled by said conveyer, means arranged between said conveyer apron and the second mentioned conveyer for stopping articles, packages, boxes, crates and the like, and means on said conveyer apron for engaging articles, packages, boxes, crates and the like delivered thereto by the said second mentioned conveyer.

5. A conveyer for raising articles, packages, boxes, crates and the like comprising a conveyer, propelling means thereon, an auxiliary conveyer at one end thereof, a conveyer apron arranged between said two conveyers, means for stopping articles, packages, boxes, crates and the like to be delivered to said conveyer apron, and means actuated by said conveyer apron to engage articles, packages, boxes, crates and the like to be delivered thereon to raise the same onto said conveyer apron, said conveyer apron being arranged to deliver articles, packages, boxes, crates and the like to the first mentioned conveyer.

6. A conveyer for elevating articles, packages, boxes, crates and the like comprising a propelling conveyer, an auxiliary conveyer arranged at one end thereof, an endless conveyer apron interposed between said two conveyers, means for stopping articles, packages, boxes, crates and the like on the second mentioned conveyer before delivering the same to the said conveyer apron, and means for raising the said articles, packages, boxes, crates and the like so stopped onto and upon the said conveyer apron, the said conveyer apron being arranged to deliver to the first mentioned conveyer.

In testimony whereof, I affix my signature, in presence of two witnesses.

HARRY E. WILLIAMS.
